Geo. F. Kimmel ATTORNEY.

UNITED STATES PATENT OFFICE.

NOBLE G. ASHLEY, OF FORT DODGE, IOWA.

STREET MARKER.

Application filed December 9, 1922. Serial No. 605,886.

To all whom it may concern:

Be it known that I, NOBLE G. ASHLEY, a citizen of the United States, residing at Fort Dodge, in the county of Webster and State of Iowa, have invented certain new and useful Improvements in Street Markers, of which the following is a specification.

This invention relates to a street marker for use at the intersection of streets, to direct the movement of traffic, and has for its object to provide in a manner as hereinafter set forth, a device of such class, for permanently indicating during the day and night, the center of an intersection in connection with cross streets, avenues and roadways.

Further objects of the invention are to provide a marker for the purpose set forth, which is simple in its construction and arrangement, strong, durable, compact, thoroughly efficient in its use, having means to prevent the shifting thereof laterally when mounted in operative position, readily assembled, requiring a small amount of labor to install and upkeep, and inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

40 Figure 1 is a longitudinal sectional view of the street marker, in accordance with this invention, showing the position thereof with respect to a man-hole.

Figure 2 is a top plan view of the marker.

45 Figure 3 is an inverted plan view.

Figure 4 is an elevation showing the manner of connecting and securing the marker in position in a road bed.

Referring to the drawings in detail, a 50 street marker in accordance with this invention is in the form of a dome shaped shell, that is to say, the segment of a hollow sphere, and is formed from any suitable ma-

terial, preferably heavy cast iron of a thickness of about three-quarters of an inch, but it is obvious that the shell can be set up of any desired thickness. The shell is indicated at 3, and is formed with a vertically disposed annular seating portion 4, at the base thereof. The edge 5, of the annular portion 4, provides a seat.

Depending from the base of the shell 3, is a plurality of securing lugs 6, these latter are formed integral with the inner face of the shell 3, and preferably are six in number, but the number of the lugs 6 can be increased or diminished as desired. That portion of the lug 6, which depends from the shell 3, is inset with respect to the annular portion 4, as indicated at 7, whereby the supporting edge or seat 5, will be extended or widened as indicated at 8. The outer face of that portion 7 of each of the lugs 6, is perpendicular, but the inner face thereof is bevelled as at 9. The lugs 6, are designed to hold the shell 3 in place when installed without the employment of any other fastening or securing devices.

As shown in Figure 1, the marker is set up with respect to a man-hole ring 10, and when in such position the marker is substituted for the man-hole cover, and when the marker is arranged in the position as shown in Figure 1, it can not be shifted laterally and it is impossible to remove the marker from the man-hole ring 10, unless the marker is lifted vertically to a height whereby the lower ends of the lugs 6, will clear the top edge of the man-hole ring 10. When the marker is set up at the intersection of the streets, when no man-hole is arranged at said intersection, the road-bed is formed with a series of pockets 11, as shown in Figure 4, for the reception of the lugs 6. When the marker is to be set up on a dirt road-bed, the lugs 6 are extended into such road-bed up to the base.

As shown in Figure 1, when the marker is set up in position with respect to the man-hole ring 10, the seat formed by the lower edge of the annular portion 4 and the inset lug is mounted on the man-hole ring 10, and the perpendicular faces of the portions 7, of the lugs 6, are positioned against the inner face of the man-hole ring 10.

The shell 3, is provided with a plurality

of openings 12, preferably four in number, but the number of openings 12, can be increased or diminished as desired, and each of said openings 12 is preferably three inches 5. in diameter, however, the diameter of each of the openings 12 can be as required. When four openings 12 are formed in the casings 3, they are positioned at about forty-five degrees apart, one from the other and arranged 10 centrally substantially one-half way between the center and the base of the shell. The wall of each of the openings 12, is provided with an annular shoulder or bead 13, and the parts of the shell 3, where the openings 12 are arranged, are thickened as at 14, for reinforcing purposes.

Mounted in each of the openings 12, is a colored lens 15, preferably red but not necessarily so, and each of the lenses 15, is 20 formed with a lateral flange 16, for seating against the shoulder or bead 13. The lenses 15 snugly engage the walls of the openings 12, and each of the lenses is bi-convex in cross section. The lenses 15, are 25 arranged inwardly with respect to the periphery of the shell 3, so as to prevent them from becoming injured or broken and are further disposed at an inclination with respect to the surface of the street and are 30 arranged at the same inclination as the inclination of the shell so as to direct the rays of light to the eyes of the driver of a vehicle.

The shell centrally thereof is provided 35 with an opening 17, with the wall thereof formed with an inwardly extending annular flange 18, which constitutes a seat and forms the opening of two different diameters with that portion of smaller 40 diameter arranged inwardly. The opening 17 is closed by a metallic plate 19, having its outer face forming a continuation of the outer face of the shell 3, and the said plate 19 is mounted on the flange 18. Hold-fast 45 devices 20, are employed for detachably connecting the flange 18, to the plate 19.

Positioned in that part of the opening 17, of smaller diameter, and abutting against the plate 19, is a circular supporting member 21, of disk-like form and preferably constructed of wood. The member 21, is secured to the plate 19, by a hold-fast device 22, the latter being arranged centrally of the plate 19. Depending from the member 50 21, is a lamp socket 23, the latter being secured to the member 21, by the hold-fast devices 24. Detachably mounted in the depending socket 23, is an electric lamp 25, having leading-in wires 26. The leading- 55 wires 26, can be coupled in any suitable manner to a source of electrical supply.

The inner face of the shell 3, is painted white to increase the brilliancy of the light and preferably 50 watt Mill type lamp is 60 employed and which consumes very little

current. The periphery of the shell 3, is of white enamel whereby it will be readily distinguishable.

A marker in accordance with this invention is constructed of very few parts and 70 the elements of construction are such that they will not get out of order and further any part that may become broken or damaged can be readily replaced as the lenses of the lamp are of a type carried in stock 75 so that they can be readily replaced when occasion requires. Preferably the marker is six and one-half inches in height from its base to its highest point, but it is obvious that the height of the marker can be 80 as desired. The hold-fast devices are countersunk so as to be flush with the periphery of the shell, whereby the periphery will be smooth at the points where the hold-fast devices are arranged. The lenses employed are of what may be termed the ordinary bull-dog lenses used in connection with the tail lights of automobiles.

From the foregoing description taken in connection with the accompanying drawings, a street marker for the intersection of cross streets is set up which will readily indicate the center of the intersection and assist in the movement of traffic, and although the preferred embodiment of the invention is as shown, yet it is to be understood that changes in the details of construction can be had without departing from the spirit of the invention as claimed.

What I claim is:—

1. A device for the purpose set forth comprising a dome-shaped shell provided with a plurality of openings, colored lenses mounted in said openings, a plurality of lugs depending from said shell, and an illuminating device suspended centrally from the top of the shell.

2. A device for the purpose set forth comprising a dome-shaped shell provided with a plurality of openings, colored lenses mounted in said openings, a plurality of lugs depending from said shell, an illuminating device suspended centrally from the top of the shell, and means to provide for the removal of said device, said means flush 110 with the periphery of the shell.

3. A device for the purpose set forth comprising a dome-shaped shell provided with a plurality of reinforced portions between its center and the base thereof and a reinforced portion at the center thereof, each of said reinforced portions formed with an opening having the wall thereof shouldered, a removable plate secured against the shoulder of said central opening, lenses extended through the other of said openings and seated against the shoulders of the walls thereof, retaining means for said shell, and an illuminating device suspended from said plate.

4. A device for the purpose set forth comprising a dome-shaped shell provided with a plurality of openings, lenses mounted in said openings, a plurality of holding lugs having the upper portions thereof integral with the inner face of the shell and the remaining portions thereof depending from and offset with respect to the inner face of the shell, and an illuminating device arranged within and suspended from the shell 10 centrally thereof, the outer faces of said lenses being inset with respect to the periphery of the shell.

In testimony whereof, I affix my signature hereto.

NOBLE G. ASHLEY.
